(57) **CLAIM**

We claim the ornamental design for a structural component of clip for holding thin film solar panels, as shown and described.

DESCRIPTION

FIG. 1 is an upper perspective view of a structural component of clip of the present disclosure with broken lines showing portions of the clip and a thin film solar panel that form no part of the claimed design;

FIG. 2 is an upper perspective view of the structural component of clip shown in FIG. 1;

FIG. 3 is a lower perspective view of the structural component of clip shown in FIG. 1;

FIG. 4 is a back elevation view of the structural component of clip shown in FIG. 1;

FIG. 5 is a front elevation view of the structural component of clip shown in FIG. 1;

FIG. 6 is a right side elevation view of the structural component of clip shown in FIG. 1, the left side elevation view being a mirror image of the right side elevation view;

FIG. 7 is a top plan view of the structural component of clip shown in FIG. 1; and,

FIG. 8 is a bottom plan view of the structural component of clip shown in FIG. 1.

The broken lines in FIGS. 1 and 6 are included for the purpose of illustrating portions of the clip and a thin film solar panel that form no part of the claimed design.

The claim has been shown broken away to indicate an indeterminate length.
